UNITED STATES PATENT OFFICE.

FRANK H. SLEEPER, OF WORCESTER, MASSACHUSETTS, ASSIGNOR TO SLEEPER & HARTLEY, INC., OF WORCESTER, MASSACHUSETTS, A CORPORATION OF MASSACHUSETTS.

CONTINUOUS WIRE-DRAWING MACHINE.

Application filed August 27, 1923. Serial No. 659,474.

To all whom it may concern:

Be it known that I, FRANK H. SLEEPER, a citizen of the Dominion of Canada, residing at Worcester, in the county of Worcester and State of Massachusetts, have invented a new and useful Continuous Wire-Drawing Machine, of which the following is a specification.

The principal object of this invention is to provide a continuous wire drawing machine in which variations in resistance will be compensated for instantaneously and smoothly so that all sudden variations in speed will be avoided. This is accomplished by providing, in place of the ordinary kinds of differential gearing, a device for driving the drums which will be controlled by and respond instantly to changes in torque so that the speed of each drum after the first one will be varied in accordance with changes in load, that is, changes in the resistance to the drawing through of the wire. More specifically, the arrangement is such that as soon as the resistance to the passage of the wire through a die is increased, the speed will slow down quickly and proportionally and when the resistance decreases the speed will increase and this will be accomplished automatically by the variations in torque on the shafts through which power is transmitted to the drum. The invention also involves a greatly simplified construction and one that is much more flexible in operation than the usual differential drives. Other objects and advantages of the invention will appear hereinafter.

Reference is to be had to the accompanying drawings, in which

Fig. 1 is a front elevation of a continuous wire drawing machine constructed in accordance with this invention;

Fig. 2 is a plan of the same;

Fig. 3 is an end view with the motor shaft in section on the line 3—3 of Fig. 2;

Fig. 4 is a transverse sectional view on the line 4—4 of Fig. 2, looking in the direction of the arrows;

Fig. 5 is a vertical longitudinal sectional view through the center of the drawing through drums, showing two of them;

Fig. 6 is an edge view of one of the pulleys for driving the drums shown partly in central section; and

Fig. 7 is a side view of the same, looking in the direction of the arrow 7 in Fig. 6.

It is well understood that several kinds of machines for the continuous drawing of wire have been in use for some years. They usually involve means for permitting variation in the speed of rotation of the drums and avoid the positive connection of the drums with their driving shafts, so that, in case of sudden increase in strain, the speed can be reduced automatically to avoid breaking the wire and yet the wire will be kept taut. For this purpose differential gearing of various kinds has been employed. However, they do not respond instantaneously to variations in resistance, so they do not work with perfect smoothness. The speed variations are more or less sudden and jerky.

While this invention is applied to the same kind of a machine the important difficulty thereof is eliminated by the present invention in that no differential gearing is employed. Instead of that I provide means whereby instantaneously when a drum tends to slow up by reason of encountering additional resistance, usually in the passage of the wire through the die, the speed of transmission to the shaft which is driving that drum will be reduced automatically and that reduction will be caused by the change in torque on that shaft. Also, the opposite operation takes place upon a decrease in torque. It will be understood that it is not a change in speed anywhere that changes the speed of the drum to compensate for it but it is change in torque itself. It is the resistance that changes the speed and therefore the operation is instantaneous and the correction of the difficulty does not lag behind the cause.

Referring now to the drawings, I have shown the wire drawing bench 1 as arranged in substantially the usual form and provided with an end frame 2 for supporting an electric motor 3 although any other kind of driving means can be employed. Through gearing 4 the motor or other driving means rotates continuously the main shaft 5. On this shaft are arranged several pulleys 6, 16, 26 and 36, preferably all of the same size. The first pulley 6 is provided with a belt which drives a pulley 9 positively fixed on a shaft 00. This shaft through bevel gears

25 drives a vertical shaft 27 connected with the first drawing through drum 28. This drum therefore is positively driven at a constant speed from the main shaft 5. The 5 second pulley 16 through a belt 7 shown in Fig 4 and belt tightener 8, drives a pulley 19 on a second shaft 10 parallel with the first shaft 00. These two shafts are shown as 10 in alignment but are entirely independent of each other.

I have provided for arranging one or both of the pulleys 16 and 19 in such a way as to accomplish the results above indicated. For the purpose of illustration, I have 15 shown the invention as applied to the pulley 19 on the driven shaft 10. If the invention were applied to the pulley 16 on the driving shaft 5 slight modifications would be made but the result would be the same and that 20 constitutes a part of this invention.

Keyed upon the shaft 10 is the hub of a flat disc 11. This disc is provided with a series of cam slots 12 all located at equal and definite angles to radial lines and at 25 equal distances apart circumferentially.

Rotatably mounted on the driven shaft 10 is the hub 13 of the pulley. This hub is intended to be connected with the shaft through the disc 11 only. It is shown as 30 bearing up against a collar 14 fixed to the shaft and as provided with a series of radial guides 15. I have shown notches 17 at the ends of these guides for a purpose to be described.

35 Mounted to move freely in the guides 15 are a series of radial slides 18. Each one of these has a pulley rim section, preferably integrally mounted on its end, and these sections taken together constitute the entire 40 rim of the pulley 19. These slides are located in the guides 15 so that they can move radially therein for the purpose of increasing and decreasing the diameter of the pulley. Each slide is provided with a projection or stud 20 on which is rotatably mounted 45 a cam roll 21. The number of these slides is equal to the number of cam slots 12 and each of these rolls 21 is placed in one of the cam slots.

50 At the rear of each slide is shown a web 22 for which the notches 17 are provided. One end of a spring 23 is secured to the web, the other end being secured to a projection 24 on the hub 13. These springs as shown 55 in these figures are arranged radially and they are extension springs in this case. Any spring or other means can be used that will tend to resist all decrease in the speed of transmission. The springs 23 tend to hold 60 the slides in toward the center and in that way they tend to resist increase in the size of the driven pulley and consequent reduction of the speed ratio. In this case they 65 also resist the action of centrifugal force if the pulley is driven fast enough to bring

that into play sufficiently to move these sections. This means is arranged to resist decreases in the speed ratio.

Power is transmitted from the belt 17 running over the rim of the pulley 19 through 70 the several slides 18 to the rolls 21. The rolls, on account of engaging the slanting surfaces of the slots 12, will move outwardly on any increase in load or torque. Therefore the belt will transmit its power to the 75 disc 11 and thus to the driven shaft 10 at a slower speed. This change in speed is governed automatically by the torque on the driven shaft. This results in the automatic and instantaneous variation in the speed of 80 transmission to avoid the breakage of the wire in case of sudden increase in resistance and also keeps the wire taut.

Although I have mentioned centrifugal force I wish it to be understood that ordinarily I do not intend to drive this pulley fast enough to have the centrifugal force exert any appreciable influence on the diameter of the pulley.

90 The shaft 10 is connected with its drawing through drum in the same way as has been described above in connection with the first shaft 00. The pulleys 26 and 36 on the driving shaft 5 are also connected with pulleys 29 and 39 on their shafts 20 and 30 in 95 the same way as the pulley 16 the same principles being applied in all these three cases. Preferably the pulleys 9, 19, 29 and 39 are all of the same size. The last pulley 39 drives through bevel gearing the winding drum 29 but otherwise conditions are the same throughout.

100 In this way I have provided an arrangement whereby the first drawing through drum is driven positively and at a constant speed but the other drawing through drums and the winding drum are driven with variable speeds governed entirely by the torque on the shafts connected with them and immediately sensitive to any changes in resistance. These changes are compensated for as and when they arise, so that they have 105 no chance to become great and the modifications in speed are made smoothly and without jar and they are relatively small.

110 It will be observed that the gear ratio increases from the first drum to the last in the usual proportions so that as the wire is drawn out the speed of the drum on which it is wound is progressively greater, as is 115 usually the case in this class of machines. This invention is not intended to change that ratio but to govern the actual speed of each of the drums after the first one in accordance with the torque.

120 This immediately reduces sudden strains while they are taking place, enables the machine to run fast if the wire is under size, and permits of uniform running as long as the wire is without changes in size 125 130

and hardness and no other obstacles intervene. In that way breakage is avoided and production is increased while the quality and uniformity of the product are improved.

It will be observed that I have provided on the shaft 00 a gear 31 for operating a crank 32 and that this operates a wire pointing device 33. I have also shown the die holders 34 and other features of the wire drawing machine which do not constitute parts of this invention.

Although I have illustrated and described only one form of the invention, I am aware of the fact that modifications can be made therein by any person skilled in the art without departing from the scope of the invention as expressed in the claims. Therefore I do not wish to be limited to all the details of construction herein shown and described but what I do claim is:—

1. In a wire drawing machine, the combination with a shaft, a wire drawing drum, means for positively gearing the shaft to said drum, driving means for the shaft comprising a belt and two pulleys connected thereby, one pulley being on said shaft, and means associated with said driving means for instantaneously and smoothly increasing the speed of said gearing when the load decreases and decreasing its speed when the load increases, said means being operated by variations in the torque on said shaft.

2. In a wire drawing machine, the combination with a wire drawing drum and a shaft for driving it, of two pulleys and a belt for driving the shaft, one of said pulleys being expansible and means for varying the speed of the shaft through the expansible pulley inversely as the torque on said shaft.

3. In a wire drawing machine, the combination with a wire drawing drum and means for driving it including two pulleys and a belt, one of said pulleys being expansible, of means located within said pulley for varying the speed of transmission of power to the drum through said expansible pulley, inversely in accordance with changes in the load.

4. In a wire drawing machine, the combination with a driving shaft, a driven shaft, a pulley on each shaft, a belt driving one pulley from the other, the pulley on one of the shafts being expansible and loosely mounted thereon, a wire drawing drum, and means for positively driving the drum from said driven shaft, of a disc in the loose pulley fixed to its shaft, and means for connecting the loose pulley and disc for transmitting power between the pulley and shaft at a speed varying inversely with the torque on that shaft.

5. In a continuous wire drawing machine, the combination with a set of drawing through and winding drums, a main shaft, pulleys on the main shaft, one for each drum, a set of driven shafts each having a pulley adapted to be driven from the respective pulley on the main shaft, positive connections between the first pulley and its driven shaft, means for connecting each of the other driven pulleys with its driven shaft and transmitting the power thereto at a speed varying with the torque, and positive gearing for connecting each driven shaft with the respective drum for normally driving each drum of the series faster than those before it.

In testimony whereof I have hereunto affixed my signature.

FRANK H. SLEEPER.
